COMBINED REFRIGERANT CYLINDER AND CARRYING HANDLE THEREFOR

Robert B. Schaefer, Malvern, Pa., assignor to Pennsalt
Chemicals Corporation, Philadelphia, Pa., a corporation
of Pennsylvania

Filed Feb. 8, 1967, Ser. No. 5,733

Term of patent 14 years

(Cl. D23—2)

Fig. 1

Fig. 2

Fig. 3

FIGURE 1 is a perspective view of a combined refrigerant cylinder and carrying handle therefor, embodying my new design.

FIGURE 2 is an enlarged top plan view.

FIGURE 3 is an enlarged front elevation view with a portion of the cylinder broken away for convenience of illustration.

FIGURE 4 is an enlarged side elevational view.

FIGURE 5 is an enlarged bottom plan view thereof.

The dominant features of this design reside in the portions shown in full lines.

I claim:

The ornamental design for a combined refrigerant cylinder and carrying handle therefor, substantially as shown and described.
